(57) **CLAIM**

The ornamental design for the a male/female connector assembly for connecting electrical conductors, as shown and described.

DESCRIPTION

FIG. 1 is a perspective view of a male connector portion of a male/female connector assembly for connecting electrical conductors showing my new design;

FIG. 2 is a front view thereof;

FIG. 3 is a rear view thereof;

FIG. 4 is a side view thereof;

FIG. 5 is a side view thereof;

FIG. 6 is a top view thereof;

FIG. 7 is a bottom view thereof;

FIG. 8 is a perspective view of a female connector portion of a male/female connector assembly for connecting electrical conductors showing my new design;

FIG. 9 is a front view thereof;

FIG. 10 is a rear view thereof;

FIG. 11 is a side view thereof;

FIG. 12 is a side view thereof;

FIG. 13 is a top view thereof; and,

FIG. 14 is a bottom view thereof.
